The ornamental design for a fence panel, as shown and described.

DESCRIPTION

FIG. 1 is a perspective view of the fence panel showing my new design, with the broken lines showing symbolic break lines in the fence panel;

FIG. 2 is a front view thereof, with the broken lines showing symbolic break lines in the fence panel;

FIG. 3 is a rear view thereof, with the broken lines showing symbolic break lines in the fence panel;

FIG. 4 is a top view thereof, with the broken lines showing symbolic break lines in the fence panel;

FIG. 5 is a bottom view thereof, with the broken lines showing symbolic break lines in the fence panel;

FIG. 6 is a right side view thereof, with the broken lines showing symbolic break lines in the fence panel; and,

FIG. 7 is a left side view thereof, with the broken lines showing symbolic break lines in the fence panel.

The symbolic break lines depict the bounds of the Claim. The area between the break lines form no part of the claimed design.
